Primary Examiner — Michelle E. Wilson*Assistant Examiner* — Caitlin A Laverty(74) *Attorney, Agent, or Firm* — Dunlap Bennett & Ludwig, PLLC; Anna L. Kinney(57) **CLAIM**

The ornamental design for a zippered fishing rod cover, as shown and described.

DESCRIPTION

FIG. 1 is a top front perspective view of a zippered fishing rod cover, showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a top front perspective view thereof, shown in a use condition with an attached shoulder strap shown in broken lines.

The broken lines shown in the drawings represent a shoulder strap portion of the zippered fishing rod cover that forms no part of the claimed design.

1 Claim, 3 Drawing Sheets(56)
